US00D941204S

(12) **United States Design Patent** (10) **Patent No.:** **US D941,204 S**
Willing et al. (45) **Date of Patent:** **** Jan. 18, 2022**

(54) **VEHICLE FRONT LOWER VALANCE**

(71) Applicant: **Ford Global Technologies, LLC**,
Dearborn, MI (US)

(72) Inventors: **Todd Willing**, East Melbourne (AU);
Paul Wraith, West Bloomfield, MI
(US); **Dong H. Park**, Canton, MI (US);
Anthony Meyer, Royal Oak, MI (US);
Martin B. Coons, Detroit, MI (US)

(73) Assignee: **Ford Global Technologies, LLC**,
Dearborn, MI (US)

(**) Term: **15 Years**

(21) Appl. No.: **29/747,535**

(22) Filed: **Aug. 24, 2020**

(51) **LOC (13) Cl.** **12-16**

(52) **U.S. Cl.**

USPC **D12/196**

(57) **CLAIM**

The ornamental design for a vehicle front lower valance, as shown and described.

DESCRIPTION

FIG. 1 is a front elevational view of a vehicle front lower valance, showing our new design;

FIG. 2 is a rear elevational view thereof;

FIG. 3 is a left side elevational view thereof;

FIG. 4 is a right side elevational view thereof;

FIG. 5 is a top plan view thereof;

FIG. 6 is a bottom plan view thereof;

FIG. 7 is a top, front and left side perspective view thereof;

FIG. 8 is a bottom, front and left side perspective view thereof; and,

(Continued)

FIG. 9 is a bottom, front and right side perspective view thereof.

1 Claim, 9 Drawing Sheets
